TWO-PIECE BAKELITE GRIP

Charles A. Bradley, Penn Township, Allegheny County, Pa., assignor to The Aluminum Cooking Utensil Company, New Kensington, Pa., a corporation of Pennsylvania

Application June 10, 1937, Serial No. 147,415

4 Claims. (Cl. 220—95)

Insulating grips for cooking utensil handles often are made of non-conducting plastic material by molding. The grips may be one-piece moldings, molded around the handle, or attached thereto by means of rivets or the like. Grips for strap handles, and particularly for curved strap handles such as bails, usually are molded around the handle in a single piece, but sometimes are made in two pieces and riveted to the bail handle. In either case, replacement of the grip when it becomes loosened or broken in use in either very difficult for the ordinary purchaser of cooking utensils or entirely beyond his skill. Furthermore, in the riveted structures, the rivet heads are generally at or near the surface of the non-conducting grip, and the rivet shank is in direct contact with the metal bail at the point at which it passes through the bail. The rivet heads heat up in such cases and may burn the hands of the user. It is an object of my invention to overcome these and other disadvantages in the construction of heat-insulating grips for handles. More particularly, it is an object of my invention to provide an insulating grip that is simple in construction and efficient in operation. Specifically, it is an object of my invention to provide an easily replaceable two-piece insulating grip for strap handles, such as bails, which is affixed to the bail in such manner that the fastening means are completely insulated from the metal of the bail to prevent conduction of heat to the surface of the grip.

Referring now to the drawing in which like reference numerals indicate like parts through the several views:

Fig. 1 is a view, partially in longitudinal section and partially in elevation, of a two-piece grip made of non-conducting plastic material according to my invention and attached to the bail of a utensil;

Fig. 2 is a longitudinal sectional view of the top member of the two-piece grip;

Fig. 3 is a bottom plan view of the top member illustrated in Fig. 2;

Fig. 4 is a longitudinal sectional view of the bottom member of the grip;

Fig. 5 is a top plan view of the bottom member illustrated in Fig. 4;

Fig. 6 is a transverse section taken on the line VI—VI of Fig. 1;

Fig. 7 is a transverse section taken on the line VII—VII of Fig. 1;

Fig. 8 is a transverse section taken on the line VIII—VIII of Fig. 2;

Fig. 9 is a transverse section taken on the line IX—IX of Fig. 2;

Fig. 10 is a transverse section taken on the line X—X of Fig. 4; and

Fig. 11 is a transverse section taken on the line XI—XI of Fig. 4.

The insulating grip of my invention is applicable to any type of cooking utensil handle and is particularly suitable as a grip for bail handles. The drawing accompanying this application shows a preferred form of my invention in which the grip is attached to a suitably apertured bail. It is to be understood that the invention is not limited to the exact form illustrated in the drawing accompanying the application, the insulating grip of the invention being susceptible to numerous adaptations which will be manifest to one skilled in the art to which the invention is directed.

In the form shown, the bail or handle is substantially arcuate lengthwise and is also arcuate in transverse section over most of its length, as indicated at 20, and best shown in Fig. 7, but centrally of the grip location has a portion 21 substantially flat in transverse section, as best shown in Fig. 6. An aperture 22 extends through the handle centrally of the grip location, and an aperture 23 extends through the handle adjacent each end of the grip location. Between each aperture 23 and the central aperture 22, another aperture 24 is provided.

The top member 25 of the grip has a central boss 26 having a shoulder and a reduced end portion and hollow bosses 27 adjacent its ends. Between the boss 26 and the bosses 27 are solid bosses 28. An internally screw-threaded insert 29, of brass or the like, is provided in each hollow boss 27, the grip member 25 being molded around the inserts so that the inserts are held positively in place.

The bottom grip member 30 is provided with a central well 31 surrounded by a raised portion 32. The well 31 is of a size and shape to receive the reduced end portion of the boss 26 on the top member. The bottom member 30 adjacent each end has a well 33 and a countersunk passage 34 extending through the member 30 into the base of each well 33. The countersunk passage 34 is adapted to register with the threaded insert in the hollow boss 27 of the top member. Between the well 31 and the wells 33, short bosses 35 of the same cross sectional size and shape as, and adapted to register with, the aforementioned bosses 28 on the top member 25, are provided.

In assembling the grip, the reduced end portion of the boss 26 is inserted through the aper-

30

35

ture 22 and into the well 31, so that the members are properly located on the handle, the bosses 28 and 35 meeting through the apertures 24, and the hollow bosses 27 extending through the apertures 5 23 into the wells 33. It will be seen that in this position, the portion of the bail surrounding the central aperture 22 is gripped by the shoulder of the boss 26 and by the raised surface 32, and that each passage 34 registers with the threaded insert 10 29 in a hollow boss 21. A flat headed screw 36 is inserted through each passage 34 into the screw-threaded insert 29 in the corresponding hollow boss 21. The assembly is completed by tightening the screws 36.

15 When the bail or handle is not in a constant or uniform arc, the grip members are made correspondingly eccentric. In some instances, this eccentricity is too slight to be apparent immediately to the eye, but in the event that one or both of 20 the members were reversed, a poorly fitting grip would result. In such cases, the grip members may be marked near one end, as by the front markers 37 and 38, which are provided in the 25 molding of the grip so that reversal of the members in assembling them may be avoided.

By this construction, the handle grip is readily and easily assembled, and comparatively easy to manufacture. The hollow bosses 27 surround the 30 inserts 29 and the shanks of the screws 36, completely insulating them from the bail or handle so that the heads of the screws do not become heated.

If a grip becomes worn or broken in use, no special skill is required to remove it and secure 35 another grip in place. It will be seen that the top and bottom members are so formed that they cannot be confused, and that the top member is in the form of a shallow channel, while the bottom member is in the form of a deeper and wider 40 channel receiving the top member, to provide a smooth surface on the grip.

I claim:

1. In a handle construction, a bail in the form of a strap having spaced apertures therein, a top 45 grip member formed of non-conducting material and having a hollow boss in each end extending through an aperture in said strap, an internally screw-threaded insert in each of said hollow bosses, a central solid boss on said top member extending through an aperture in said strap, a bottom grip member formed of non-conducting material and having a well at each end receiving one of said hollow bosses and defining a passage 50

through said bottom member, and a central well in said bottom member receiving said central boss on said top member.

2. In a handle construction, a bail in the form of a strap having spaced apertures therein, a top 5 grip member formed of non-conducting material and having a hollow boss in each end extending through an aperture in said strap, an internally screw-threaded insert in each of said hollow bosses, a central solid boss on said top member 10 extending through an aperture in said strap, a bottom grip member formed of non-conducting material and having a well at each end receiving one of said hollow bosses and defining a passage through said bottom member registering with one 15 of said inserts, and a central well in said bottom member receiving said central boss on said top member.

3. In a handle construction, a bail in the form of a strap having spaced apertures therein, a top 20 grip member formed of non-conducting material and having a hollow boss in each end extending through an aperture in said strap, an internally screw-threaded insert in each of said hollow bosses, a central solid boss on said top member 25 extending through an aperture in said strap, a bottom grip member formed of non-conducting material and having a well at each end receiving one of said hollow bosses and defining a passage through said bottom member registering with one 30 of said inserts, a central well in the said bottom member receiving said central boss on said top member, and complementary positioning means comprising solid bosses on said top and bottom members meeting at apertures in said strap. 35

4. In a handle construction, a bail in the form of a strap having spaced apertures therein, a top grip member formed of non-conducting material and having a hollow boss in each end extending through an aperture in said strap, an internally 40 screw-threaded insert in each of said hollow bosses, a central solid boss on said top member extending through an aperture in said strap, a bottom grip member formed of non-conducting material and having a well at each end receiving one of said hollow bosses and defining a passage 45 through said bottom member registering with one of said inserts, a central well in the said bottom member receiving said central boss on said top member, and molded assembly markers at one end 50 of each of said grip members.

CHARLES A. BRADLEY.
